UNITED STATES PATENT OFFICE.

CARL SODERLUND, OF BELMONT, MASSACHUSETTS, ASSIGNOR TO HOOD RUBBER COMPANY, OF WATERTOWN, MASSACHUSETTS, A CORPORATION OF MASSACHUSETTS.

BOOT-TREE OR LAST.

Application filed February 17, 1927. Serial No. 168,980.

My said invention relates to improvements in boot trees or lasts of the type used for manufacturing rubber boots and the like. These are customarily made of metal having a separable toe piece to facilitate removal of the last from the completed boot, the leg and toe portions having abutting faces which lie in intersecting planes, one of which is disposed substantially lengthwise of the last and the other substantially perpendicular thereto, constituting a substantially L-shaped joint.

The invention aims to provide such a tree or last of exceedingly simple and durable construction in which the toe section is secured to the leg section by a connection permitting a limited sliding movement relative thereto when removal is desired, but preventing total disconnection whereby the toe section is withdrawn with the leg section.

The invention further aims to provide a connection between the parts which will permit a pivotal movement of the toe section relative to the leg section to facilitate removal.

The invention further aims to provide simple and efficient means for holding the parts with their abutting faces pressed into intimate contact, which means may be automatically disengaged by a pull upon the leg section and as readily engaged by reverse movement.

In order that the invention may be more readily understood, reference is made to the accompanying drawings, in which:—

Figure 1 is a side elevation of what I at present consider the preferred embodiment of the invention, the lower part being shown in section.

Fig. 2 is a similar view showing the parts in the position assumed when being withdrawn from a boot.

Fig. 3 is a section on line 3—3 of Fig. 1.

Fig. 4 is a bottom view of the last.

Fig. 5 is a section on line 5—5 of Fig. 1.

Referring by reference characters to this drawing, the numeral 1 designates the main or leg section of the tree or last and 2 the toe section, these having abutting faces disposed in intersecting planes indicated at A and B, the former, as is customary, being

arranged substantially lengthwise of the leg portion and the latter being substantially perpendicular thereto.

To effect a limited sliding connection between the parts, I provide one of them, say the toe section 2, with a slotted guide which projects into a guide-way in the abutting face of the other part. In the embodiment shown the guide-way is formed by merely providing a slot in the face 1^a of the leg section (as by cutting).

The slotted guide is formed by a bar 3 of strap iron or the like spaced from the lengthwise face of the last to form the slot, 65 said bar having its lower end rigidly secured to a lug 2^b projecting from the face 2^a of the toe section at the lower end thereof. As these lasts are usually made of aluminum castings, which is relatively light, I 70 prefer, for purposes of strength, to provide a special lug construction which comprises spaced integral projections 2^c, Fig. 4 between which is secured the steel lug block (2^b) to which the lower end of the bar 3 is 75 secured by a tap screw 3^a. Preferably the face 2^a is provided with a relatively low flange projection 2^d (Fig. 5) which forms a tongue and groove fit with the guide-way in the face 1^a of the body of the last, and 80 which cooperates with bar 3 to form the slotted guide.

The main portion of the bar 3 is parallel to the face of the flange or rib 2^c and forms therewith the slotted guide which receives 85 a transverse pin or bar 5 carried by the walls of the body portion of the last near the lower end thereof (the last being made hollow, as shown, for lightness).

The bar 3 has its upper portion first inclined outwardly towards the back of the last as indicated at 3^b, and then forwardly in spaced relation thereto as indicated at 3^c to form an inclined guide-way communicating at its lower or front end with the slotted 95 guide-way formed by the parallel wall of the bar 3 and rib 2^c.

The bar further has an upwardly and forwardly inclined end 3^d which forms a tongue extension or member cooperating 100 with a spring detent 6 secured to the inner face of the front portion of the leg mem-

ber just above the intersection B in the manner hereinafter described.

The portion of the bar 3 between the parts 3^c and 3^d is flattened and secured to the upper face of the toe section. For purposes of strength and also to accommodate itself to the hollow formation of the last, I prefer to provide a cross bar 7 of steel or other hard metal secured to the upper face of the toe section by tap screws, the overlying portion of bar 3 being secured to this bar 7 by means such as a bolt or rivet.

The leg portion 1 is transversely recessed as shown at 1^e to receive the bar 7. The detent spring 6 is arranged so as to incline backwardly towards the rear of the last and has a terminal reversely inclined portion 6^a, providing an intervening nose 6^b and the end of portion 3^d is rounded to cooperate therewith.

By reason of the sliding engagement of pin 5 in the guide-way formed by the member 3 cooperating with the rib 2^c, the toe section may be slid lengthwise of the main section 1. When shoved to the limit of its upward movement the rounded end of the part or tongue member 3^d engages the inclined portion 6^a of spring 6 and deflects the latter until said rounded end rides over the nose and lodges behind the same, as shown in Fig. 1. In this position the nose holds the toe section against downward movement relative to the body of the last and also by reason of its pressure towards the rear of the last holds the vertical faces of the toe and body sections (along intersection A) pressed tight together.

When the last is to be removed from the completed boot, a pull upon the leg section causes the end of 3^d to ride over the nose 6^b as will be evident. Upward movement of the leg section causes the pin 5 to move upward in the guideway until it is deflected into the upper inclined portion thereof, at which time the toe section will tilt into the position shown in Fig. 2, to permit withdrawal from the boot, the toe section remaining connected with the leg section.

Having thus described my invention, what I claim is:—

1. A boot tree or last comprising a leg section and a toe section having faces abutting along intersecting planes which are substantially lengthwise and transverse to the body of the last respectively, the lengthwise face of the leg section having a guideway, a bar secured at its ends to the lengthwise face of the toe section and spaced therefrom and forming therewith a guide, said guide projecting into said guideway, a transverse pin carried by the leg section near its lower end and passing through the space between said bar and the adjacent face of the toe section, and spring detent means interposed between the leg and toe sections adjacent the upper

end of the latter for releasably holding them in abutting relation.

2. A boot tree or last comprising leg and toes sections having faces abutting along intersecting planes which are substantially lengthwise and transverse to the body of the last respectively, the lengthwise face of the leg section having a guideway, a slotted guide carried by the lengthwise face of the toe section projecting into said guideway, said guide including a bar arranged parallel to the said face of the toe section, said bar having its upper portion inclined away from the toe portion and then turned back upon itself to form an inclined guide slot extension, means securing said turned back portion to the upper part of the toe section, a transverse pin carried by the leg section near its lower end and passing through the slotted guide, and spring detent means interposed between the leg and toe sections adjacent the upper end of the latter.

3. A boot tree or last comprising leg and toe sections having faces abutting along intersecting planes which are substantially lengthwise and transverse to the body of the last respectively, the lengthwise face of the leg section having a lengthwise guideway, a slotted guide carried by the lengthwise face of the toe section and having a guide slot extension at its upper end inclined towards the rear of the last, a pin carried by the leg section adjacent its lower end and engaging said slotted guide, and spring detent means interposed between the leg and toe sections adjacent the upper end of the latter.

4. A boot tree or last comprising leg and toe sections having faces abutting along intersecting planes which are substantially lengthwise and transverse to the body of the last respectively, the lengthwise face of the leg section having a lengthwise guideway, a slotted guide carried by the lengthwise face of the toe section and having a guide slot extension at its upper end inclined towards the rear of the last, a pin carried by the leg section adjacent its lower end and engaging said slotted guide, a leaf spring secured to the inside face of the leg section adjacent the transverse face and having a nose with inclined portions on each side thereof, and a tongue member carried by the toe section at the upper end thereof to cooperate with said spring.

5. A boot tree or last comprising leg and toe sections having faces abutting along intersecting planes which are substantially lengthwise and transverse to the body of the last respectively, the lengthwise face of the leg section having a guideway, a slotted guide carried by the lengthwise face of the toe section projecting into said guideway, said guide including a bar arranged parallel to the said face of the toe section, said bar having its upper portion inclined away from

the toe portion and then turned back upon itself to form an inclined guide slot extension, means securing said turned back portion to the upper part of the toe section, said turned back portion having an integral tongue extension inclined upwardly towards the front of the last, a transverse pin carried

by the leg section adjacent its lower end and passing through the slotted guide, and a spring detent carried by the leg section and 10 engaging said tongue extension.

In testimony whereof, I affix my signature.

CARL SODERLUND.
